H. E. FENCHELLE,
STARTING VALVE FOR INTERNAL COMBUSTION ENGINES,
APPLICATION FILED DEC. 6, 1917.

1,294,078.

Patented Feb. 11, 1919.

UNITED STATES PATENT OFFICE.

HUGH EMILE FENCHELLE, OF GENOA, ITALY, ASSIGNOR TO WILLIAM L. KANN, OF PITTSBURGH, PENNSYLVANIA, TRUSTEE.

STARTING-VALVE FOR INTERNAL-COMBUSTION ENGINES.

1,294,078.

Specification of Letters Patent. Patented Feb. 11, 1919.

Application filed December 6, 1917. Serial No. 205,889.

To all whom it may concern:

Be it known that I, HUGH EMILE FENCHELLE, a British subject, residing at Via XX Settembre 34/4, Genoa, in the Kingdom 5 of Italy, have invented certain new and useful Improvements in Starting-Valves for Internal-Combustion Engines, of which the following is a specification.

This invention relates to air starting 10 valves for internal combustion engines, especially those employing a Diesel type of ignition, and has for its chief object to provide an automatically acting valve of this type which opens only when the pressure 15 within the cylinder is below that of the starting air supply so that there is no risk of the compressed air or gases in the cylinder being driven back into the air supply apparatus.

According to this invention the valve stem 20 slides within a sliding piston under the control of an interposed spring, the piston being displaceable between a fixed stop and a stop on the valve stem, against which latter 25 stop it is forced by the pressure of the starting air admitted to the valve casing, so as to hold the valve closed by the air pressure until the piston is displaced by the engine starting mechanism to release the valve and 30 allow it to open and close automatically in accordance with the relative pressures of the starting air and cylinder gases.

In order that the said invention may be 35 more clearly understood and readily carried into effect the same will be more fully described with reference to the accompanying drawing, which shows in longitudinal section an air starting valve embodying this invention.

A is the valve stem with mushroom head a at the inner end and an adjustable stop nut a' at the outer end. B is the displaceable piston and C the valve casing within 40 which the piston and valve slide. D is a piston operating lever with connection d through which it can be actuated by a cam on the distributing shaft so as to control the position of the piston B. For this purpose, the short arm d' of said lever is of forked 45 form, this forked end being arranged to engage the collar b on the piston.

Between the collar b on the upper end of the piston B and the nut a' on the end of the valve stem A is placed a spring a'' which 55 serves to hold the valve a resiliently upon

its seating at the end of the valve casing and also to keep the piston B down so that the flange or stop b' normally rests upon the upper end of the casing C.

On starting air being admitted to the 60 valve chamber a' through the port a' in the casing the air pressure is exerted both upon the valve head a and upon the lower end of the piston B. The area of the latter being greater than that of the valve the piston 65 is driven upwardly by the excess pressure so as to compress the spring a'', the movement continuing until the upper end of the piston extension b' meets the under surface of the stop nut a' on the valve stem. The 70 valve in this position is therefore firmly held closed by the pressure of the air acting on the piston and no starting air can escape into the cylinder. To provide for the starting action the lever D, which is mounted 75 upon the bracket E, is operated from the distributing shaft so as to press the piston B down against the pressure of the air in the chamber a'. The piston is displaced until it reaches the position shown in the drawing, with the flange b' abutting against the upper end of the casing C. The valve is now free to open against the relatively small pressure of the spring a'' and to admit the starting air to the cylinder. If however, the pressure in the cylinder is greater than the starting air pressure the valve remains closed and only in the event of the cylinder pressure falling on expansion below the pressure of the starting air will the 80 valve open and admit the air into the cylinder. The valve is thus a balanced one and opens and closes in accordance with the relative pressures of the starting air and the 85 cylinder gases.

When the air in the valve casing is placed to exhaust the valve is held upon its seat by the aforesaid spring a'' and thus serves at this time, as well as during the time that the starting air is in communication with 90 the valve casing, as a check valve for preventing admission of the cylinder gases or air into the valve casing and the starting air channels.

What I claim and desire to secure by Letters Patent of the United States is:—

1. In apparatus of the character described, a casing having an air chamber provided with a constantly open inlet, and with an outlet leading to the cylinder, a valve 110

- 2
- controlling said outlet and exposed at all times to the cylinder pressure in a seating direction and to the pressure in said chamber in an unseating direction, a piston slidably mounted in said casing and also slidable on the stem of the valve with one end thereof opposed to the said valve and exposed to the air pressure in said chamber, the piston and valve having coöperating stop portions, and a spring interposed between the piston and valve, and means for positively displacing the piston against the air pressure in said chamber to thereby release the valve from the control of the piston.
- 15 2. In air starting apparatus for internal combustion engines, an automatic air starting valve, a valve casing, a sliding piston in the casing, subjected to the pressure of the starting air, through which piston the valve passes, a stop on the valve stem adapted to meet the piston when the latter is pressed back by the starting air, a light spring between the valve and piston, maintaining the valve normally closed and the piston in an operative position, and means for displacing the piston against the pressure of the air so as to release the valve from piston control.
3. In air starting apparatus for internal combustion engines, an automatic starting valve comprising a valve stem and a mushroom head, a valve casing, a sliding piston in the casing and exposed to the starting air pressure, an adjustable stop on the valve stem against which the piston is pressed by the pressure of the starting air, a spring
- between the piston and valve and means for displacing the piston against the pressure of the starting air so as to release the valve from piston control.
4. In air starting apparatus for internal combustion engines, an automatic starting valve comprising a valve stem and a mushroom head, a valve casing, a sliding piston in the casing and exposed to the starting air pressure, a stop on the piston adapted to abut against the casing when the piston is in normal inoperative position, an adjustable stop on the valve stem against which the piston is pressed by the pressure of the starting air, a spring between the piston and valve and means for displacing the piston against the pressure of the starting air so as to release the valve from piston control.
5. An automatic air starting valve for internal combustion engines, comprising a cylindrical casing having a valve chamber at one end, a sliding valve stem with mushroom head closing the said chamber, a piston adapted to slide in the casing and receiving the sliding valve stem, the area of the piston exposed to the pressure of starting air in the valve chamber being greater than that of the valve surface exposed to such pressure, a stop upon the outer end of the valve stem against which stop the piston abuts on the admission of starting air to the valve chamber, and means for displacing the piston against the pressure of the starting air.

HUGH EMILE FENCHELLE.
